UNITED STATES PATENT OFFICE.

PHILIP H. SHUE, OF DENVER, COLORADO, ASSIGNOR OF ONE-HALF TO GEORGE M. ROBINSON, OF DENVER, COLORADO.

PUMP.

1,036,919.

Specification of Letters Patent. Patented Aug. 27, 1912.

Application filed April 19, 1911. Serial No. 622,028.

To all whom it may concern:

Be it known that I, PHILIP H. SHUE, a citizen of the United States of America, residing at Denver, in the county of Denver and State of Colorado, have invented certain new and useful Improvements in Pumps, of which the following is a specification.

This invention relates to improvements in pumps and its principal object resides in the provision of a mechanism which, by the use of air under compression, will raise water from deep wells and other inaccessible places and deliver it in a substantially continuous stream at a point of higher elevation.

My invention includes to this end, a system of coöperative elements, one of which is submerged in the fluid to be raised while the others are actuated by the flow and weight of the elevated water to direct a current of air under compression alternately into separate compartments of the submerged element.

Inasmuch as the operative parts of the mechanism are installed above the surface of the water and separate from the conduits through which the fluid is conducted from its source to its point of delivery, they cannot possibly be affected by sand and other solids contained in the water and this feature in connection with the simplicity of construction of the apparatus, render the invention serviceable in places where skilled mechanics are not readily available and the water elevating devices are operated, adjusted and if necessary repaired by persons inexperienced in the construction of machinery.

An embodiment of my invention is illustrated in the accompanying drawings in the various views of which like parts are similarly designated and in which—

Figure 1 represents a sectional elevation of the apparatus. Fig. 2, a vertical elevation partially in section along the line 2—2 Fig. 1. Fig. 3, a plan view of the uppermost element shown in the preceding figures. Fig. 4, a transverse section along the line 4—4 Fig. 2. Fig. 5, a similar section taken along the line 5—5 Fig. 2, and Fig. 6, a section taken along the line 6—6, Fig. 1.

My improved pump comprises, essentially, three coöperative elements respectively des-

ignated in the drawings by the letters A, B 55 and C. The element A consists of a receiver 2 which in the operation of the invention is submerged in the body of water to be raised such as that contained in a well shown at D in the drawings. The receiver which is 60 preferably made of sheet-metal and cylindrical in form is, by means of an upright partition 3, divided into two compartments 4 and 5 which are provided at their respective bottoms, with openings the flow through 65 which is controlled by back pressure valves 6 and 7. The receiver 2 is furthermore provided with a delivery chamber 8 provided by a transversely disposed inclosure which has in its bottom portion two valves 9 and 70 10 which control openings communicating respectively with the two compartments 4 and 5.

A stand pipe 12 is connected at its lower end with the delivery chamber 8 and two 75 conduits 13 and 14 lead respectively from the compartments 4 and 5 to a valve-chest 15 comprised in the element B, which by means of pipe 16 communicates with a compressor, reservoir or other source of compressed air. The face-plate 20 of the chest 15 is provided with two inlet ports 17 and 18 which respectively connect with the conduits 13 and 14, and an interposed exhaust port 24 through which the compartments of 80 the receiver may be brought in communication with the atmosphere and which also serves to admit the means whereby the D-valve 19 slidably supported upon the plate 20, is operated. 90

The means above referred to consist of a bell-crank lever 21 which is fulcrumed upon a hanger 22, and whose arms connect respectively with a central depression formed in the interior surface of the slide-valve and 95 with the lower extremity of a pitman 23, which at its opposite end is pivotally attached to a lever 25 of the uppermost element C which is designed for the automatic operation of the valve 19 by the flow and 100 weight of the water discharged from the stand pipe 12. The lever 25 is composed of a rectangular frame which at a point intermediate its extremities is fulcrumed upon a supporting structure 26. Two buckets 27, 105 of equal weight and capacity, are suspended from the arms of the lever at equal distances from its fulcrum and each of these buckets

has in its bottom a plurality of radial discharge openings the flow through which is controlled by means of a rotary disk-valve 28. The stems 29 of these valves projecting below the respective buckets are flattened to move slidably through slots cut in plates 30 which extend horizontally from the supporting structure 26 and the said stems are twisted so that when by downward movement of the buckets with which they are associated, they are drawn through their respective slots, they will impart a rotary movement to their respective valves to either close or open the openings in the bottoms of the receptacles 27.

The lever 25 when at rest, is slantingly supported at one of its extremities upon one or the other of two stops which normally project into the arcual paths of said extremities when moving about the fulcrum. Each of these stops is composed of a lever 31 which is fulcrumed upon a post 32 and which at its end engaged by the lever, is provided with an upwardly movable trip 33 which while adapted to arrest the downward motion of the adjacent arm of the lever, will permit it to pass in the opposite direction without affecting the lever of which the trip forms part. The opposite arms of the levers 31 carry poises 34, and stops 35 secured to the posts 32 are provided to limit the movement of the levers by gravitational action of said poises. The buckets 27 are made of sufficient size to each receive the contents of one of the compartments of the receiver 2 and the poises 34 are proportioned so that they will be overbalanced by the buckets when the latter are filled above a predetermined point. The connection between the end of the pitman 23 and the lever 25 is established at a point at one side of the fulcrum of the latter so that when the position of the lever is reversed, the slide valve 19 will be moved through the instrumentality of the bell-crank 21 to vary its position with relation to the ports in the plate upon which it is slidably supported. The stand pipe 12 connects at its upper extremity with a branch 36 which projects horizontally above and in a vertical plane with the fulcrum of the lever 25, and which at a point intermediate its ends, has a downwardly directed nozzle 37. A trough 38 is pivotally mounted upon the branch 36 to receive the fluid discharged through the nozzle 37, and it extends, when at rest, slantingly in a direction opposite to that of the lever 25. A link 40 connects an end of the trough at one side of the plane of the axes of oscillation of the two members, with the arm of the lever at the opposite side of said plane so that when the lever is moved about its fulcrum a similar movement in the opposite direction will be imparted to the trough 38. An inclined flume 39 disposed

below the buckets 27 is provided to conduct fluid discharged from the buckets to its point of destination.

Having thus described the mechanical construction of my invention, its operation will be readily understood. With the elements comprised in the invention arranged as shown in the drawings, the receiver is lowered into the body of water to be raised and the valve-chest is brought in communication with the source of compressed air, the degree of compression in which exceeds the weight of the column of fluid to be elevated. Presuming that the parts are in the position shown in Fig. 1, it will be observed that the valve 19 has established communication between the compartment 5 of the receiver 2 and the atmosphere, while the opposite compartment 4 of the same is in communication with the interior of the valve chest which by means of the conduit 16 is continuously supplied with air under compression, the latter flowing into the compartment forces the water contained therein through the opening controlled by the valve 9, into the delivery chamber 8 whence it rises in the stand pipe 12. The intake valve 6 of the same compartment is at the same time held upon its seat by the pressure of water and air while the corresponding valve 7 which controls the inlet opening of the other compartment 5, is opened by the pressure of the water in which the receiver is submerged, and thus allows the water to enter the compartment until the position of the slide valve 19 is reversed. The last named action is automatically performed by means of the water which, having risen in the stand pipe, is discharged through the nozzle 37 into the trough 38 through which it flows into the bucket 27 at the upper end of the lever 25. When the bucket is in this position the openings in its bottom are closed by the valve 28 and the water is discharged thereinto from the trough 38 until its level has reached a determinate point, when the combined weights of the bucket and its contents will over-balance the poise at the end of the lever 31 upon which the lever 25 is supported. The latter is in consequence moved about its fulcrum by the gravitational influence of the loaded bucket, until its position is reversed. During the downward motion of the loaded bucket, the openings in its bottom are opened by the movement of its valve induced by the longitudinal motion of its twisted stem through the slot in the respective plate 30 and its contents are thus discharged into the subjacent flume 39. Motion of the lever 25 about its fulcrum caused the slide valve 19 to reverse its position, through the instrumentality of the bell crank 21 and the pitman 23, and the position of the trough 38 is simultaneously reversed through the agency of the link 40.

As a result of the above described actions the compartment 5 of the receiver 2 is now brought in communication with the source of compressed air, the compartment 4 connects with the atmosphere through the exhaust port 24, the bucket at the opposite end of the lever 25 is in the raised position to receive the water flowing through the trough 38 and the openings in the bottom thereof have been closed during the upward movement of the lever 29 through the slot in the respective plate 30. The conditions presumed at the beginning of the description of the operation of the invention are thus reversed and the flow of the water from the stand pipe will continue to effect alternate operations of the elements and thus produce a substantially continuous flow of water, through the flume 39.

Having thus described my invention what I claim and desire to secure by Letters-Patent is:—

1. An apparatus of the class described comprising an element having two separate receiving chambers each having a valve-controlled opening to admit liquid in which said element is submerged, and a delivery chamber having valve-controlled openings communicating respectively with the two receiving chambers, a source of compressed air, a stand pipe connected with the delivery-chamber, conduits connected respectively with the said receiving chambers, a valve adapted to connect said conduits alternately with said source, a horizontal lever movable about a central fulcrum, buckets suspended at equal distances from said fulcrum and having discharge-openings, valves controlling the flow through said openings and having twisted stems, a relatively stationary plate having openings in which said stems are slidably fitted, means for directing the flow of liquid discharged from the stand-pipe alternately into said buckets, a launder disposed to receive liquid discharged from said buckets and a mechanism for transmitting the movements of the lever to the said valve.

2. An apparatus of the class described comprising an element having two separate receiving chambers each having a valve controlled opening to admit liquid in which said element is submerged, and a delivery chamber having valve controlled openings communicating respectively with the two receiving chambers, a source of compressed air, a stand-pipe connected with the delivery-chamber, conduits connected respectively with the said receiving chamber, a

valve adapted to connect said conduits alternately with said source, a horizontal lever movable about a central fulcrum, buckets suspended at equal distances from said fulcrum, an oscillatory trough disposed to receive liquid discharged from the stand-pipe and to deliver it through its opposite ends into the respective buckets, a link for transmitting the movements of said lever into movements of said trough in the opposite direction, means for discharging the contents of the buckets during downward movement thereof, a launder disposed to receive liquid discharged from said buckets and a mechanism for transmitting the movements of the lever to the valve.

3. An apparatus of the class described comprising an element having two separate receiving chambers each having a valve controlled opening to admit liquid in which said element is submerged, and a delivery-chamber having valve-controlled openings communicating respectively with the two receiving chambers, a stand pipe connected with the delivery chamber, a source of compressed air, and a mechanism adapted to be actuated by the gravity of predetermined quantities of fluid discharged from the stand-pipe, unaided by other forces, to bring said receiving chambers alternately in communication with said source.

4. An apparatus of the class described comprising an element having two separate receiving chambers each having a valve-controlled opening to admit liquid in which said element is submerged, and a delivery chamber having valve-controlled openings communicating respectively with the two receiving chambers, a stand pipe connected with the delivery chamber, a source of compressed air, and mechanism adapted to be actuated by the gravity of predetermined quantities of fluid discharged from the stand-pipe to bring said receiving chambers alternately in communication with said source, said quantities being equal to a portion of the contents of either of said receiving chambers whereby the said chambers are at all times maintained partially filled with liquid, and the mouth of the stand pipe in the delivery chamber is continually sealed against the inflow of air.

In testimony whereof I have affixed my signature in presence of two witnesses.

PHILIP H. SHUE.
